MINNOW TRAP

Lewis E. Hamel, Rochester, N. Y., assignor to
 Lewis E. Hamel Co., Inc., Rochester, N. Y., a
 corporation of New York

Application July 3, 1947, Serial No. 758,778

12 Claims. (Cl. 43—105)

1

This invention relates to a minnow trap, and has for its purpose to afford a collapsible structure made from plastic material which can be quickly and easily assembled in operative position, and which is foldable into a compact, flat package when not in use.

The invention has for a further purpose to afford a construction that is practical and convenient to use, which can be economically manufactured, and requires a minimum number of parts.

More particularly the invention has for its object to afford a structure including side walls and end walls in hinged relation and maintained in operative position by means of a transverse retaining partition that is interlocked with each one of the side walls and includes latch means for releasably holding the separable side walls in predetermined relation and maintaining all the walls firmly in operative positions.

Still another purpose of the invention is to afford an arrangement in which the hinge connections between the side and end walls and the hinge connections between adjacent end walls are integral with the side and end walls and do not require separate pintles or additional parts for maintaining the necessary hinged relationship to permit folding.

To these and other ends, the invention consists in the construction and arrangement of parts that will appear clearly from the following description when read in conjunction with the accompanying drawings, the novel features being pointed out in the claims following the specification.

In the drawings:

Fig. 1 is a view in end elevation, showing the parts in operative position;

Fig. 2 is a view in side elevation of the same, looking from right to left of Fig. 1;

Fig. 3 is a plan view of the same;

Fig. 4 is a transverse sectional view taken centrally of Fig. 2, showing the transverse retaining partition in elevation interlocked with the side walls and locked to the adjacent portions of the separable side walls;

Fig. 5 is a view in end elevation showing the position of the parts when two connected side walls have been released from the remaining side walls and transverse retaining partition and folded one upon the other, previously to removing the transverse retaining partition and folding the other two side walls;

Fig. 6 is a plan view, partially broken away, showing the parts in folded or collapsed rela-

tion, with the transverse retaining partition removed;

Fig. 7 is a longitudinal sectional view on line 7—7 of Fig. 6;

Fig. 8 is a transverse sectional view on line 8—8 of Fig. 6;

Fig. 9 is a transverse sectional view on line 9—9 of Fig. 6;

Fig. 10 is a partial perspective view of the 10 transverse retaining partition;

Fig. 11 is a detail sectional view on line 11—11 of Fig. 4, showing a latch of the transverse retaining partition in locked relation;

Fig. 12 is a similar view, showing the transverse retaining partition moved laterally with relation to the latch opening, to release the side wall when the device is to be collapsed;

Fig. 13 is a detail perspective view of one end 15 of a side wall, partially broken away;

Fig. 14 is a sectional perspective view on line 14—14 of Fig. 13, and

Fig. 15 is a detail view in elevation showing the hinge connection between two end walls.

Referring more particularly to the drawings in 25 which like reference numerals refer to the same parts throughout the several views, 1 and 2 designate side walls formed of suitable plastic material pivoted together to swing outwardly in relation to each other for collapsing, and to this 30 end the walls 1 and 2 are provided with interengaging integral hinge knuckles 3 connected by the pintles 9 which are also preferably of plastic material. The walls 1 and 2 are perforated to permit free circulation of water to the interior

35 of the trap, while 5 and 6 designate the other two side walls which are pivotally connected respectively to the walls 1 and 2 to swing inwardly in relation thereto for collapsing. The walls 5 and 6 are also formed of plastic material and per-

40 forated similarly to the walls 1 and 2, and hingedly connected thereto by means of the knuckles 7 and 8 formed integrally with the several walls and connected by means of the pintles 9 of plastic material.

45 Referring to Figs. 1 and 4, it will be observed that the hinge knuckles 3 are formed beyond the outer edges of their supporting side walls to permit relative outward folding of the walls 1 and 2 while the knuckles 7 and 8 are formed with-

50 in the outer surfaces of their supporting side walls to permit relative inward folding thereof, as will be described hereinafter. When the trap is folded or collapsed, the walls 5 and 6 fold inwardly on the walls 1 and 2 respectively, and the

55 walls 1 and 2 with the walls 5 and 6 lying flatly

thereagainst, are then folded outwardly to the collapsed position illustrated in Figs. 6 and 7, the end walls to be described presently folding simultaneously with the side walls. When the walls are in unfolded or operative position, they are held and locked together by a transverse retaining partition which braces and gives rigidity to the entire assembly, as will now be described.

The transverse retaining partition is shown in Figs. 4 and 10 to 12 inclusive, and is indicated generally at 11, being cut away centrally as at 12 to provide an enlarged opening for movement of water and minnows within the trap. The retaining partition 11 is of generally square shape and fits snugly against the inner surfaces of the side walls when the latter are in operative relationship. In order to maintain the side walls firmly against movement, the retaining partition 11 is provided with interlocking means engaging each of the side walls, preferably in the form of extensions 13 that engage openings or recesses in the side walls 1, 2 and 6. The extensions 13 preferably terminate at points approximately flush with the outer surfaces of the side walls which they engage, while one edge of the retaining partition 11 is provided with an extension 14 that projects through the opening in the wall 5 and exteriorly thereof to afford a handle that may be provided with a finger opening 15 for carrying the trap when ready for operating and to enable suspending it in water by a suitable rope or chain.

16 designates an opening in the upper portion of the retaining partition 11 within the trap, and from which can be suspended suitable bait 17 held by a string 18 for attracting minnows into the trap, and the retaining partition 11 is preferably cut away at its corners, as indicated at 19, to enable its fitting more readily against the side walls without interference. The meeting edges of the side walls are preferably bevelled, as indicated at 21, Fig. 4, to permit a close, rigid fit and to enable more readily bringing the walls 5 and 6 together into locked engagement with the retaining partition 11, as will now be described.

The retaining partition 11 is held in more or less fixed relation to the several walls by means of the interlocking extensions and recesses already described, and in order to lock the side walls 5 and 6 firmly in engagement with the retaining partition 11, the latter is provided with latches 22 and 23 formed integral with the retaining partition 11 and extending upwardly and laterally therefrom, as shown in Fig. 10. These latches operate in opposite directions, the latch 22 extending upwardly through opening 24 in the side wall 5 and the nose of said latch extending over said side wall toward the left of Figs. 2 and 3, while latch 23 extends laterally through opening 25 in side wall 6 and the nose of said latch extends over the surface of said side wall toward the right of Figs. 2 and 3. When the parts are assembled as in Fig. 4, latches 22 and 23 on the retaining partition lock the walls 5 and 6 and hold them securely against separation.

The openings 24 and 25 are slightly larger than the latches 22 and 23 so that latch 23, which extends exteriorly of the wall 6, can be engaged and pressed laterally to the left of Figs. 2 and 3, there being sufficient spring or flexibility to the retaining partition 11 to permit this movement, whereupon the side wall 6 is released and can be swung downwardly and inwardly on to the side wall 2 in the manner shown in Fig. 5, the trap being

preferably turned over and supported on the wall 1 during this operation. Then by engaging latch 22 and moving it slightly laterally of wall 5, the side wall 5 is released and can be swung away to release the central retaining partition 11 which can be lifted away from engagement with wall 1. After the central retaining partition 11 is removed, wall 5 can be folded inwardly on wall 1, and the walls 4 and 2 then folded outwardly to bring the walls into the collapsed position illustrated in Figs. 6 and 7. To unfold the walls and assemble them in operative position, they are first positioned as illustrated in Fig. 5, and the handle portion 14 of the central retaining partition together with latch 22 are inserted through the openings in side wall 5, the central retaining partition 11 being then brought into interlocking engagement with side wall 1 by inserting its extension into the corresponding opening in the side wall, after which the walls 2 and 6 are unfolded and swung upwardly around the retaining partition 11 from the position shown in Fig. 5 until they engage the interlocking projecting portions on the retaining partition 11. Then by pushing the side wall 6 over latch 23, the latter springs into engagement with the opening in said side wall and locks it in position and the parts are securely and rigidly held against accidental displacement.

It will be understood from the foregoing description that the side walls and the central retaining partition are each formed of an integral sheet of plastic material, so that the structure thus far described requires only five pieces of plastic material in addition to the plastic pins for engaging the hinge knuckles already described. In order to close the ends of the trap so as to permit minnows to enter from either end and prevent their escape, each side wall is provided with an end wall pivotally connected thereto for folding when collapsing and so constructed and related as to permit the folding operations already described and to afford a funnel-shaped opening at each end of the trap when the parts are operatively positioned.

This is preferably accomplished by providing the side walls 1 and 5 with end walls 27 and 28 respectively which are hingedly connected to said side walls and to each other, see Fig. 1, as will be described presently, and the side walls 2 and 6 are similarly provided with end walls 29 and 31, respectively, that are hinged to the side walls and to each other, the end walls when in operative position extending inwardly of the trap at acute angles to the side walls, as shown in Figs. 1 to 3, and affording a generally funnel-shaped closure with a small square opening 32 central thereof through which minnows can enter the trap. Each end wall consists of a generally trapezoidal integral sheet or plate of plastic material and is connected to its supporting end wall by means of hook-shaped integral hinge portions 33 that extend through openings 34 in the connected side wall and engage the cylindrical pintles 35 formed integral with the side wall. The hinge portions 33 are held in hinged relation to the pintles 35 by means of a locking portion or lug 36 preferably arranged intermediate the hinge portions 33 and formed integral with the end wall, the lug 36 extending over the opposite surface of the side wall and engaging the side wall oppositely to the surface engaged by the hinge portions 33 as they enter the openings 34, while 37 designates a recess or cut-away portion formed in the side wall 75 in alignment with the lug 36 on the end wall to

accommodate the lug when the end wall is swung at an angle to the side wall and permit the necessary movement of the end wall from collapsing to operative position.

Referring to Fig. 1, it will be understood that the locking portion or lug 36 overlies the adjacent portion of the side wall to which the end wall is connected while the hinge portions 33 underlie the integral pintles 35, so that lug 36 thus retains the end wall in proper hinged relationship and prevents accidental separation from its connected side wall. The end wall is constructed of a thin sheet of plastic material and is sufficiently flexible to permit flexing it to attach it to the connected side wall. This is accomplished by flexing the end wall along its hinged edge sufficiently to position the lug 36 and hinge portions 33 against opposite surfaces of the side wall, then by sliding the end wall bodily until the hinge portions 33 register with openings 34, and releasing the end wall, the hinge portions spring into the openings 34 in engagement with the pintles 35. After such assembling and release of the end wall, it assumes its normal flat relation and is held locked in hinged relation to the side wall by means of the oppositely positioned overlying lug 36.

Each end wall is connected to its supporting side wall in this fashion, and each pair of adjacent end walls are connected in the manner illustrated in Fig. 15. Each end wall is cut away along a straight line at its inner end, as indicated at 32, to afford the square central opening when in operative position, and one end wall of the pair is provided with an integral hook-shaped hinge portion 39 that enters a slot 41 in the adjacent end wall and engages a pintle 42 formed integral with the adjacent end wall, while a locking portion or lug 43 formed integral with the first mentioned end wall engages the opposite surface of the adjacent end wall and prevents separation of the hinge portion. It will be understood that in assembling a pair of hinged end walls, the lug 43 is initially positioned against one surface of the adjacent end wall, referring to Fig. 15, and the outer portion of the end wall carrying the lug 43 is then flexed laterally to a sufficient extent to permit the hinge portion 39 to move over the opposite surface and drop into the slot 41. When released, the end wall assumes its flat position and is held in hinged relationship to the adjacent end wall, it being understood that the two connected end walls are hinged to the supporting side walls in the manner already described.

Thus when the parts are folded as shown in Figs. 6 to 9 inclusive, each pair of hinged end walls fold together between the side walls to which they are connected, assuming the positions illustrated in Figs. 6 and 7. In order to accommodate the hinge portions 39 of the end walls when folded, the side walls are provided with suitable recesses or depressions 39a formed adjacent thereto to receive said hinge portions, as indicated in Fig. 9, and in order to protect the hinge knuckles when the walls 1 and 2 are folded outwardly upon each other for collapsing, as shown in Fig. 7, said walls are provided on their outer surfaces with integral abutments or projections 44, see Fig. 7, which are located opposite one another for engagement to limit movement of the side walls when folded and prevent excess pressure on the hinge knuckles. The separable meeting edges of the walls 5 and 6 are recessed or cut away to provide the interengaging portions 45 and 46, see Figs. 2 and 3, that insure correct po-

sitioning and holding of said walls in interlocked relation when the trap is completely assembled for operation.

While the structure has been described with reference to the particular embodiment herein shown, it is not confined to the structural details disclosed, and this application is intended to cover such modifications or departures as may come within the purposes of the improvements or the scope of the following claims.

- 10 I claim:
1. In a minnow trap comprising two perforate side walls of plastic material hinged together and foldable outwardly in relation to each other for collapsing, a perforate side wall of plastic material hinged to each of the first mentioned side walls and foldable inwardly thereon for collapsing, and a transverse centrally cut-away retaining partition of plastic material removably and interlockingly engaged with said four side walls, said partition including integral extensions each of which engages an opening in one of said side walls to interlock therewith and permit separation of the partition from all four side walls.
  2. In a minnow trap comprising two perforate side walls of plastic material hinged together and foldable outwardly in relation to each other for collapsing, a perforate side wall of plastic material hinged to each of the first mentioned side walls and foldable inwardly thereon for collapsing, and a transverse centrally cut-away retaining partition of plastic material removably and interlockingly engaged with said four side walls, said partition including integral extensions each of which engages an opening in one of said side walls to interlock therewith and permit separation of the partition from all four side walls and said retaining partition having integral oppositely acting latch portions extending through openings adjacent to the meeting edges of the separable side walls and releasably engaging the last mentioned side walls to lock the parts in operative position.
  3. In a minnow trap comprising two perforate side walls of plastic material hinged together and foldable outwardly in relation to each other for collapsing, a perforate side wall of plastic material hinged to each of the first mentioned side walls and foldable inwardly thereon for collapsing, a transverse centrally cut-away retaining partition of plastic material removably engaging said side walls, integral interlocking extensions on said retaining partition projecting into openings in the side walls, and integral oppositely acting latch portions on said partition extending into openings adjacent to the meeting edges of the separable side walls and releasably engaging the last mentioned side walls to lock the parts in operative position.
  4. In a minnow trap comprising two perforate side walls of plastic material hinged together and foldable outwardly in relation to each other for collapsing, a perforate side wall of plastic material hinged to each of the first mentioned side walls and foldable inwardly thereon for collapsing, a transverse centrally cut-away retaining partition removably engaging said side walls, interlocking portions on said retaining partition projecting into openings in the side walls, and integral oppositely acting latch portions on said partition extending through openings adjacent to the meeting edges of the separable side walls and releasably engaging the last mentioned side walls to lock the parts in operative position, one

of said interlocking portions extending through and exteriorly of its side wall and having a finger opening therein comprising a handle.

5. In a minnow trap comprising two perforate side walls of plastic material hinged together and foldable outwardly in relation to each other for collapsing, a perforate side wall of plastic material hinged to each of the first mentioned side walls and foldable inwardly thereon for collapsing, and a transverse centrally cut-away retaining partition of plastic material removably and interlockingly engaged with said side walls, said partition including integral extensions each of which engages an opening in one of said side walls to interlock therewith and permit separation of the partition from all four side walls, and said retaining partition having integral oppositely acting latch portions extending through openings adjacent to the meeting edges of the separable side walls and releasably engaging the last mentioned side walls to lock the parts in operative position, the separable side walls having separable interlocking portions at their meeting edges for holding them in predetermined operative relation.

6. In a minnow trap comprising two perforate side walls of plastic material hinged together and foldable outwardly in relation to each other for collapsing, a perforate side wall of plastic material hinged to each of the first mentioned side walls and foldable inwardly thereon for collapsing, a transverse centrally cut-away retaining partition of plastic material removably engaging said side walls, interlocking extensions on said retaining partition projecting into openings in the side walls, and integral oppositely acting latch portions extending through openings adjacent to the meeting edges of the separable side walls and releasably engaging the last mentioned walls to lock the parts in operative position, the separable side walls having separable interlocking portions at their meeting edges for holding them in predetermined operative relation.

7. In a minnow trap comprising two perforate side walls of plastic material hinged together and foldable outwardly in relation to each other for collapsing, a perforate side wall of plastic material hinged to each of the first mentioned side walls and foldable inwardly thereon for collapsing, a transverse centrally cut-away retaining partition removably engaging said side walls, interlocking portions on said retaining partition projecting into openings in the side walls, and integral oppositely acting latch portions extending through openings adjacent to the meeting edges of the separable side walls and releasably engaging the last mentioned walls to lock the parts in operative position, the separable side walls having interengaging portions at their meeting edges for holding them in predetermined operative relation, one of said interlocking portions extending through and exteriorly of its side wall and having a finger opening therein comprising a handle.

8. A minnow trap comprising two perforate side walls of plastic material hinged together and foldable outwardly in relation to each other for collapsing, a perforate side wall of plastic material hinged to each of the first mentioned side walls and foldable inwardly thereon for collapsing, and end walls of plastic material and generally trapezoidal in shape hinged to the ends of each side wall, each end wall having a pair of spaced integral hook-shaped hinge portions

extending through openings in the adjacent side wall and engaging pintles integral therewith and an intermediate integral locking portion engaging the opposite surface of said side wall between the hinge portions and preventing separation of the side and end walls, the end wall on each inwardly folding side wall and on the adjacent outwardly folding side wall being hinged together along one side edge to afford with the other end walls a funnel-shaped inlet when in operative position, one of said hinged end walls having an integral hook-shaped hinge portion extending through an opening in the adjacent end wall and engaging a pintle integral therewith and an integral locking portion engaging the opposite surface of the adjacent end wall to prevent their separation.

9. A minnow trap comprising two perforate side walls of plastic material hinged together and foldable outwardly in relation to each other for collapsing, and a perforate side wall of plastic material hinged to each of the first mentioned side walls and foldable inwardly thereon for collapsing, a transverse centrally cut-away retaining partition removably and interlockingly engaged with said side walls, end walls of plastic material and generally trapezoidal in shape hinged to the ends of each side wall, each end wall having a pair of spaced integral hook-shaped hinge portions extending through openings in the adjacent side wall and engaging pintles integral therewith and an intermediate integral locking portion engaging the opposite surface of said side wall between said hinge portions and preventing separation of the side and end walls, the end wall on each inwardly folding side wall and on the adjacent outwardly folding side wall being hinged together along one side edge to afford with the other end walls a funnel-shaped inlet when in operative position, one of said hinged end walls having an integral hook-shaped hinge portion extending through an opening in the adjacent end wall and engaging a pintle integral therewith and an integral locking portion engaging the opposite surface of the adjacent end wall to prevent their separation.

10. A minnow trap comprising two perforate side walls of plastic material hinged together and foldable outwardly in relation to each other for collapsing, and a perforate side wall of plastic material hinged to each of the first mentioned side walls and foldable inwardly thereon for collapsing, a transverse centrally cut-away retaining partition removably and interlockingly engaged with said side walls, said retaining wall having integral oppositely acting latch portions extending through openings adjacent to the meeting edges of the inwardly folding side walls and releasably engaging the last mentioned walls to lock the parts in operative position, end walls of plastic material and generally trapezoidal in shape hinged to the ends of each side wall, each end wall having a pair of spaced integral hook-shaped hinge portions extending through openings in the adjacent side wall and engaging pintles integral therewith and an intermediate integral locking portion engaging the opposite surface of the side wall between said hinge portions and preventing separation of the side and end walls, the end wall on each inwardly folding side wall and on the adjacent outwardly folding side wall being hinged together to afford with the other end walls a funnel-shaped inlet when in operative position, one of said end walls having an integral hook-shaped hinge portion extend-

ing through an opening in the adjacent end wall and engaging a pintle integral therewith and an integral locking portion engaging the opposite surface of the adjacent end wall to prevent their separation.

11. A minnow trap comprising two perforate side walls of plastic material hinged together and foldable outwardly in relation to each other for collapsing, and a perforate side wall of plastic material hinged to each of the first mentioned side walls and foldable inwardly thereon for collapsing, a transverse centrally cut-away retaining partition removably engaging said side walls, interlocking portions on said retaining partition projecting into openings in each of the side walls, integral oppositely acting latch portions extending through openings adjacent to the meeting edges of the inwardly folding side walls and releasably engaging the last mentioned walls to lock the parts in operative position, end walls of plastic material and generally trapezoidal in shape hinged to the ends of each side wall, each end wall having a pair of spaced integral hook-shaped hinge portions extending through openings in the adjacent side wall and engaging pintles integral therewith and an intermediate integral locking portion engaging the opposite surface of the side wall between said hinge portions and preventing separation of the side and end walls, the end wall on each inwardly folding side wall and on the adjacent outwardly folding side wall being hinged together to afford with the other end walls a funnel-shaped inlet when in operative position, one of said end walls having an integral hook-shaped hinge portion extending through an opening in the adjacent end wall and engaging a pintle integral therewith and an integral locking portion engaging the opposite surface of the adjacent end wall to prevent their separation.

12. A minnow trap comprising two perforate side walls of plastic material hinged together and foldable outwardly in relation to each other for collapsing, and a perforate side wall of plastic material hinged to each of the first mentioned side walls and foldable inwardly thereon

for collapsing, a transverse centrally cut-away retaining partition removably engaging said side walls, interlocking portions on said retaining partition projecting into openings in each of the side walls, integral oppositely acting latch portions extending through openings adjacent to the meeting edges of the inwardly folding side walls and releasably engaging the last mentioned walls to lock the parts in operative position, end walls of plastic material and generally trapezoidal in shape hinged to the ends of each side wall, each end wall having a pair of spaced integral hook-shaped hinge portions extending through openings in the adjacent side wall and engaging pintles integral therewith and an intermediate integral locking portion engaging the opposite surface of the side wall between said hinge portions and preventing separation of the side and end walls, the end wall on each inwardly folding side wall and on the adjacent outwardly folding side wall being hinged together to afford with the other end walls a funnel-shaped inlet when in operative position, one of said end walls having an integral hook-shaped hinge portion extending through an opening in the adjacent end wall and engaging a pintle integral therewith and an integral locking portion engaging the opposite surface of the adjacent end wall to prevent their separation, one of said interlocking portions extending through and exteriorly of its side wall and having a finger opening therein comprising a handle.
